H. T. BUSSMANN

ELECTRIC FUSE

Original Filed May 7, 1919

FIG. 1

FIG. 2

INVENTOR

HENRY T. BUSSMANN,
by *Raymond. Attorney.*

UNITED STATES PATENT OFFICE.

HENRY T. BUSSMANN, OF ST. LOUIS, MISSOURI.

ELECTRIC FUSE.

Original application filed May 7, 1919, Serial No. 295,368. Divided and this application filed January 17, 1922. Serial No. 529,969.

To all whom it may concern:

Be it known that I, HENRY T. BUSSMANN, a citizen of the United States, residing at St. Louis, Missouri, have invented a certain new and useful Electric Fuse, of which the following is a full, clear, and exact description, such as will enable others skilled in the art to make and use the same.

This application is a division of application Serial No. 295,368 filed May 7, 1919.

My invention relates to electric fuse links and the object of my invention is to provide a fuse link that will operate satisfactorily under any conditions.

15 In the drawings, Fig. 1 is a view of my improved fuse link and Fig. 2 a side view showing a cross section thereof.

This fuse link has a center portion 3 of greater cross section than the balance of the link. Near the terminal portions 4, I provide an insulating material as at 5. This insulating material serves two purposes. It

conducts the heat away from the portion of the link to which it is attached, which feature, combined with the greater cross section of the center portion, causes the strip to melt at the two points 6, 6. It also acts as an arc shield, preventing injury to the terminals of the fuse, that would otherwise be caused by the arc, following the melting 30 of the fuse.

It will be understood that I may vary the location and quantity of insulating material about the link without departing from the scope of my invention, and it is equally obvious that I may use my fuse as an open link fuse or in an enclosed fuse.

What I claim is:

A fuse link having end portions and an intermediate portion, the end portion being 40 of substantially uniform reduced cross section and an arc shield upon an end portion thereof.

HENRY T. BUSSMANN.
